UNITED STATES PATENT OFFICE

164,499

TOILET SEAT ADAPTOR OR SIMILAR ARTICLE

Walter A. Inman, Waukegan, Ill., assignor to Waukegan Baby Seat Co., Waukegan, Ill., a corporation of Illinois

Application October 19, 1950, Serial No. 12,631

Term of patent 14 years

(Cl. D4—5)

To all whom it may concern:

Be it known that I, Walter A. Inman, a citizen of the United States and a resident of the city of Waukegan, county of Lake, and State of Illinois, have invented a new, original, and ornamental Design for a Toilet Seat Adaptor, or Similar Article, of which the following is a specification, reference being had to the accompanying drawing, forming a part thereof.

On the drawing:

Figure 1 is a perspective view of the toilet seat adaptor, or similar article, showing my new design; and

I claim:
The ornamental design for a toilet seat adaptor, or similar article as shown.

WALTER A. INMAN.
